Des. 233,634

Patented Nov. 19, 1974

233,634

HOSPITAL GOWN

Dana R. Snider, 241 E. Burrows,
Tucson, Ariz. 85704

Filed May 24, 1973, Ser. No. 363,427

Term of patent 14 years

Int. Cl. D2—01

U.S. Cl. D2—17

FIG. 1 is a rear perspective view of the hospital gown showing my new design;

FIG. 2 is a front elevational view thereof on a reduced scale; and

FIG. 3 is a fragmentary view in enlarged scale of the upper part of the hospital gown showing one sleeve in an open position and the other sleeve in a partially open position.

I claim:

The ornamental design for a hospital gown, as shown.
